UNITED STATES PATENT OFFICE.

WILLIAM F. LUICK, OF MILWAUKEE, WISCONSIN.

IDENTIFICATION-CARD HOLDER.

1,378,179.

Specification of Letters Patent. Patented May 17, 1921.

Application filed July 13, 1920. Serial No. 395,824.

To all whom it may concern:

Be it known that I, WILLIAM F. LUICK, a citizen of the United States, and resident of Milwaukee, in the county of Milwaukee and State of Wisconsin, have invented certain new and useful Improvements in Identification-Card Holders; and I do hereby declare that the following is a full, clear, and exact description thereof.

10 My invention refers to identification means for factory owned containers wherein the same are shipped to customers and returned for reshipment.

The object of my invention is therefore 15 to provide a simple, economical and effective holder for a combined shipping and identification card, the construction and arrangement of the holder being such that the card is thoroughly protected, and at the same time it cannot be inadvertently detached, but can be removed for renewal or 20 for change of customer by a deliberate action, with the assistance of some convenient instrument or tool, it being understood that 25 the tags are frictionally held in place and protected by a skeleton frame surrounding them.

To illustrate the use of my invention, for 30 example, in the manufacture and distribution of ice cream, tubs are utilized in shipping. These tubs are the property of the factory and a customer is allotted a predetermined number. Tags are then filled out with the customer's address and he is 35 given an arbitrary number which is more or less conspicuously displayed upon the tag. The tags are then slipped into frames embodying one of the features of my invention, which frames are permanently se- 40 cured to the tubs and form protectors for the cards or tags, which are visibly displayed. Hence with this identification card, when the receptacles are returned in large quantities from different customers, 45 the returns from each customer can readily be checked up by his number and should it be found that one of the customers is delinquent in returning the tubs, he is promptly notified. Thus it will be seen 50 that the tubs of each customer can be kept track of in the factory, so as to facilitate business, it being understood that for economic reasons the factory supply of tubs is approximately limited to the demand, 55 and hence, if the returns are not made promptly shipments are clogged.

By actual usage of my invention over a period of some months, it has been demonstrated that the identification cards are always intact and the returned receptacles 60 are thus readily checked up. Heretofore, this was impossible and due to this fact, the problem of keeping track of empties has been a serious one for many years. Under the old system, the customer's tub was 65 marked by ordinary shipping tags with various means for attaching them, and in some instances, these tags were water-proof and otherwise made from tough material so as to prevent loss of them, but owing to 70 the rough usage, the tags were found inadequate and in a short time, a large per cent. of the returned tubs contained no stub of the original tags whereby said tubs could be identified, and the factory under these 75 conditions would be unable to give the shipper credit. Furthermore, it frequently happens that another customer who neglects making prompt returns receives credit for tubs, while a customer who has been prompt 80 in his returns has been charged up as delinquent.

It should be borne in mind that this return identification is the important feature of the invention, as in practice, the freight 85 or express companies, irrespective of the tags, will see to it that the receptacles are delivered, but the empties are neglected and this is the important feature so far as the manufacturer is concerned. 90

With the above objects in view, my invention consists in what is herein shown, described and called for in the claim.

In the drawing,—

Figure 1 represents a fragment of a tub 95 or receptacle having attached thereto a skeleton frame containing an identification and shipping tag, embodying the features of my invention.

Fig. 2 is a horizontal section through 100 the same, the section being indicated by line 2—2 of Fig. 1.

Fig. 3 is a rear face view of the skeleton frame, the same being shown detached from a receptacle, and 105

Fig. 4 is a longitudinal sectional view through the frame and its integral bail ear connection, the section being indicated by line 4—4 of Fig. 1.

Referring by characters to the drawing, 1 110 represents a fragment of tub provided with the usual upper band 2. A bail ear is

adapted to this portion of the tub as shown, and the same comprises a web portion 3 which is secured to the tub body by suitable screws as shown. The web is also provided 5 with a horizontal recess 4, which in conjunction with the face of the tub, forms a sleeve 4' for a handle or bail member 5 of the usual type. The ends of the sleeve 4' have extending therefrom stop lugs 6 against 10 which the shank of the bail engages when the same is swung outwardly to sustain the load of the tub. Extending above the stop lugs and sleeve and merging into them is a skeleton frame 7, in this instance the same 15 being of rectangular formation so as to display a shipping and identification card A. The corners of the skeleton frame are formed with apertured ears for the reception of retaining screws 8, which serve in 20 conjunction with the web screws to firmly attach the bail ear to the tub. Thus by this distribution of the screws in upper and lower groups with relation to the points of strain upon the ear, the same is rendered less 25 liable to breakage, due to the balanced connections.

As best shown in Fig. 3 of the drawing, the lower stretch 9 of the frame is formed with a slight depression 10, which depression 30 is merged into corresponding depressions 10' of the vertical stretches 11 of the frame and these depressions are also extended transversely of the upper frame stretch 12 so as to form an open throat through which 35 the cards may pass into the frame, and be removed therefrom.

The vertical stretches 11 of the skeleton frame are also formed with slight transverse depressions 13, as best shown in Fig. 40 3 to permit clearance for the band 2 of the tub, it being understood that these depressions as shown are of slightly less depth than the depressions 10 and 10', which form the tag pocket. Thus it will be seen by referring especially to Fig. 4 of the drawing 45 that when the bail ear is in position and the card A inserted within the pocket, the said card is frictionally held in place by contact with the inner face of the skeleton frame on 50 one side and contact with the band 2 upon its rear face. Owing to the fact that the band 2 is of a material thickness, its outer face will serve to give the card a slight central bulge with relation to its grip in the 55 upper and lower edges, to more effectively

prevent the card from slipping out of the pocket in usage.

From the foregoing description, it will be seen that the card is thus firmly held in place and is also protected at all of its edges 60 so as to prevent damage, this protection being due to the comparatively great thickness in cross section of the skeleton frame stretches, and also to the fact that the sleeve 65 4' is offset to form, in conjunction with its other functions, a protecting element.

Referring now to the method of applying my invention, a group of the cards are directed to, for example, a shipper John Doe, and these cards contain the date of shipment, etc. and also an arbitrary number given to the shipper which, in this instance is 10. Hence, even though the shipping directions all become blurred or wiped out, 70 the printed number 10 will remain intact 75 and when the container or tub is returned to the factory, the shipper returning it is given credit, due to the fact that his number shows upon the card.

Previously while I have particularly described my invention and its usage in connection with a tub for ice cream, it is understood that I do not wish to limit my invention to any specific container, as for example, the invention can be applied to various 85 other products, wherein the containers are to be returned to the factory or plant, such for example as milk, creamery products or the like.

I claim:

In combination with a cylindrical container having hoops thereon, a shipping card holder for attachment to said container comprising a skeleton frame, said frame being transversely curved and attached to said receptacle to extend over a hoop on the cylindrical wall thereof, the under side of said frame being offset to provide a shallow card pocket having a throat extending therefrom, said offset portion following the curved contour of the frame whereby the card inserted therein is transversely bowed and held by the hoop to cause the same to be frictionally held against accidental displacement or removal. 100 105

In testimony that I claim the foregoing I have hereunto set my hand at Milwaukee, in the county of Milwaukee and State of Wisconsin.

WILLIAM F. LUICK.
